CLAIM

We claim the ornamental design for a stand for television, as shown and described.

DESCRIPTION

FIG. 1 is a front perspective view of a stand for television showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1; and,

FIG. 9 is a front perspective view of the stand for television in which a television is provided in broken lines to illustrate an example environment.

(Continued)

The broken lines in the figures show portions of the stand for television which form no part of the claimed design.
The dot-dash broken lines encircling enlargement portions of the design form no part of the claimed design.

1 Claim, 8 Drawing Sheets
